T. L. WOOD

TOY TRAIN

Filed Jan. 25, 1924

Inventor
T. L. Wood,

Clara A. O'Brien
Attorney

UNITED STATES PATENT OFFICE.

THOMAS L. WOOD, OF DALLAS, TEXAS.

TOY TRAIN.

Application filed January 25, 1924. Serial No. 688,469.

To all whom it may concern:

Be it known that I, THOMAS L. WOOD, a citizen of the United States, residing at Dallas, in the county of Dallas and State of Texas, have invented certain new and useful Improvements in Toy Trains, of which the following is a specification.

This invention relates to toys of the character simulating a railroad train and it consists in the novel features hereinafter described and claimed.

An object of the invention is to provide a toy of the character stated which includes an engine adapted to be manually operated for propulsion along a track by a juvenile and which includes trailers in the form of a tender, coaches and the like, there being provided suitable means for coupling the trailers with each other and with the engine to complete the train.

A further object of the invention is to provide the engine with structural features adapted to be adjusted in order that the parts may be suitably positioned to be conveniently operated by children of different sizes or ages.

With this object in view, the engine comprises a wheel mounted frame simulating that of an actual locomotive, and one of the shafts of one set of the driving wheels is provided with a set of cranks having foot pedals mounted thereon. A seat structure is adjustably mounted within the cab of the engine and the seat may be occupied by the operator. The seat may be adjusted transversely of the crank shaft, hereinbefore mentioned, in order to provide suitable and sufficient space between the seat and the crank shaft to adapt the device to the anatomy of the particular individual who is operating the engine.

In the accompanying drawing:—

Figure 1 is a side elevation of the toy train with parts broken away and parts shown in section.

Figure 2 is a top plan view of the running gear of the engine and with the super-structure thereof removed.

As illustrated in the accompanying drawing, the engine includes a pony truck 1 which is pivotally connected with the frame of the engine in a usual manner. The engine also includes a body 2 simulating that of a boiler and upon which is mounted a bell 3 and a whistle 4. A cab structure 5 is located at the rear end of the boiler body 2. A platform 6

forms the floor of the cab and parallel guides 7 are mounted upon the upper surface of the platform 6. A seat structure 8 is mounted upon the platform and is provided with cleats 9 which are received in the spaces between the guide members 7 whereby the seat structure may be adjusted longitudinally of the engine.

The forward set of drivers 10 of the driving wheels is mounted upon a shaft 11 which is provided with cranks 12 located between the said driving wheels and arranged to swing in arcs under the rear portion of the boiler and the forward portion of the cab. Foot pedals 13 are journaled upon the cranks 12 of the shaft 11 and the occupant of the seat 8 may place his feet upon the pedals and by using the seat as a fulcrum and working the legs in a usual manner, the shaft 11 is rotated whereby the drivers 10 are rotated and may move over the track rails 14 or their equivalent in a usual manner.

It is apparent that the seat may be adjusted to accommodate children of different sizes in order that they may conveniently and effectually reach the pedals and operate the drivers with which they are connected.

A bellows 14 is mounted upon the boiler body 2 and is arranged to discharge a blast of air in the whistle 4 when operated. Means for operating the bellows includes a lever 15 fulcrumed upon a bracket 16 and bearing at its free end against the sides of the bellows frame. A cable 17 is connected with one end of the lever and is trained back through the cab and is within reach of the occupant of the seat 8, so that the occupant while propelling the engine may draw upon the cable and swing the lever to vamp the bellows and cause the same to force a blast of air through the whistle 4 and sound the whistle in a usual manner.

A hook-shaped coupling member 18 is pivotally connected with the rear portion of the platform 6 and is adapted to interengage with a similar member provided at a forward end of the tender 19. A similar coupling member is mounted at the forward end of the engine frame and all of the trailers of the train are provided at their opposite ends with such coupling members.

A rod 19 is pivotally connected at its inner end with each of the coupling members 18 and the intermediate portion of the rod 19 is passed transversely through an eye 20 mounted at the edge portion of the vehicle

whereby the rod member 19 is held substantially in a horizontal position but may slide longitudinally. Each rod 20 is provided at its outer end with a handle 21 and the 5 said handle is disposed at or beyond the outer surface of the track rails upon which the train may travel.

From the foregoing description, taken in conjunction with the accompanying drawing, it will be seen that a toy simulating a 10 railroad train is provided and that the toy may be easily and conveniently operated by children of different sizes, to effect the propulsion of the toy over a track or its equivalent and that means are provided for giving signals simulating those which are of 15 an audible nature and which are provided upon railway equipment, and in order to produce in miniature the realistic effect of

the sounding of the signals and as will be 20 instructive and amusing to those who are observing the operation of the equipment as well as instructive to the operator.

Having described the invention, what is 25 claimed is:—

A toy vehicle comprising a body simulating that of a locomotive, forward and rear sets of driving wheels mounted upon axles journaled under the rear portion of the body, pitman rods connecting the forward and rear driving wheels, the axle of the forward set of driving wheels having 30 pedals and cranks, and an operator's seat mounted upon the body above the axle of the rear set of driving wheels. 35

In testimony whereof I affix my signature.

THOMAS L. WOOD.
